US0D1055146S

(12) **United States Design Patent** (10) Patent No.: **US D1,055,146 S**
(45) Date of Patent: ** Dec. 24, 2024

(54) **SUNGASSES**

(71) Applicant: **Waytura (Shanghai) Technology Co., Ltd.**, Shanghai (CN)

(72) Inventors: **Xin Cheng**, Wuhan (CN); **Xiaoli Shi**, Dangyang (CN)

(**) Term: **15 Years**

(21) Appl. No.: **35/518,452**

(22) Filed: **Sep. 23, 2022**

(80) **Hague Agreement Data**

Int. Filing Date: **Sep. 23, 2022**

Int. Reg. No.: **DM/223739**

Int. Reg. Date: **Sep. 23, 2022**

Int. Reg. Pub. Date: **Sep. 29, 2023**

(51) **LOC (14) Cl.** **16-06**

(52) **U.S. Cl.**

USPC **D16/329**; D16/338

(58) **Field of Classification Search**

USPC D16/300, 306, 323, 325–327, 329, 338, D16/341; D24/110.2; D29/102, 104–110

CPC G02C 7/16; G02C 11/02; G02C 1/06

See application file for complete search history.
